CLAIM

The ornamental design for a combined receptacle cap and capsule piercing device therefor, substantially as shown and described.

DESCRIPTION

FIG. 1 is a top perspective view of a combined receptacle cap and capsule piercing device therefor showing our new design;

FIG. 2 is an exploded top perspective view thereof;

FIG. 3 is a side elevational view thereof;

FIG. 4 is a top plan view thereof;

FIG. 5 is a bottom plan view thereof; and

FIG. 6 is a cross sectional view thereof taken on line 6—6 of FIG. 2.
